UNITED STATES PATENT OFFICE

WILLIAM REICHERT, OF MAMARONECK, NEW YORK

DESIGN FOR A BRACELET OR SIMILAR ARTICLE

Application filed January 21, 1930. Serial No. 34,203. Term of patent 3½ years.

To all whom it may concern:

Be it known that I, WILLIAM REICHERT, a citizen of the United States, and a resident of Mamaroneck, in the county of Westchester and State of New York, have invented the new, original, and ornamental Design for a Bracelet or Similar Article, of which the following is a specification.

Reference is had to the accompanying drawing, forming part thereof, wherein—

I claim:—

The ornamental design for a bracelet or similar article substantially as shown.

WILLIAM REICHERT.
